2 SHEETS—SHEET 2.

UNITED STATES PATENT OFFICE.

GEORGE H. LANGEHENNIG, OF GUTHRIE, OKLAHOMA.

ICE-BOX.

1,125,697.

Specification of Letters Patent. Patented Jan. 19, 1915.

Application filed July 13, 1914. Serial No. 850,772.

To all whom it may concern:

Be it known that I, GEORGE H. LANGEHENNIG, citizen of the United States, residing at Guthrie, in the county of Logan 5 and State of Oklahoma, have invented certain new and useful Improvements in Ice-Boxes, of which the following is a specification.

This invention relates to ice-boxes and has 10 for its object the provision of simple, compact and efficient mechanism whereby the quantity of ice within the ice-box at any time will be automatically indicated and the total amount of ice consumed during a given 15 period will be automatically registered.

The invention, also, seeks to provide a mechanism for the stated purpose which may be applied to refrigerators without materially decreasing the capacity of the 20 same and which will be automatically rendered inoperative when the door to the ice-box is opened and will be permitted to operate when the door is closed.

The objects of my invention are attained 25 in such a device as is illustrated in the accompanying drawings, and the invention consists in certain novel features which will be hereinafter first described and then more particularly pointed out in the appended 30 claims.

In the drawings, Figure 1 is a perspective view of a refrigerator having my improvement applied thereto. Fig. 2 is an enlarged horizontal section through the ice-box. 35 Fig. 3 is a vertical section through the operative elements of the ice-box. Fig. 4 is a detail perspective view of the ice carrier, and Fig. 5 is a detail perspective view of one of the controlling bars.

The refrigerator 1 may be of any preferred construction, being provided at a proper point with a door 2 closing the entrance to the ice chamber. This door 2 is provided on its inner side at its opposite 45 edges with projections or cams 3 and 4 which are adapted when the door is closed to bear upon lateral projections or lugs 5 and 6 at the front ends of the controlling bars 7 and 8 respectively. These controlling 50 bars 7 and 8 extend horizontally from front

to rear of the refrigerator at the sides of the ice chamber and are loosely supported at their rear ends in brackets 9, as shown most clearly in Fig. 2. The intermediate portions of the controlling bars 7 and 8 55 pass through guides 10 provided upon tracks 11 in which run the rails 12 secured rigidly upon the opposite sides of the ice support. One of these rails is provided with a smooth outer face adapted to be engaged by the controlling bar 8 under the influence of a spring 13 which is housed within the adjacent guide and bears against the said controlling bar so as to throw the same against the rail when the door 2 is 60 opened. The rail 12 at the opposite side of the ice holder is constructed with a longitudinal series of rack teeth 14 which are adapted to be engaged by a projection 15 upon the controlling bar 7 so as to positively prevent movement of the ice carrier when the door 2 is opened, the controlling 65 bar being moved toward the adjacent track under the influence of a spring 16 housed within the adjacent guide. 70

The ice carrier consists of a pan or platform 17 provided with an outlet 18 for the water formed by the melting of the ice which outlet in practice telescopes into a pipe or tube leading through the bottom of 80 the refrigerator so as to carry off the water as will be readily understood. The pan or platform 17 is secured to the lower ends of standards 19 which are connected at their upper ends by a cross bar 20, and a similar 85 standard 21 is secured to the rear end of the pan and has its upper end connected by a bar 22 to the said cross bar or arch 20, as shown clearly in Fig. 4. 75

Braces 23 are provided to secure stability 90 in the pan at such points as may be deemed desirable by the maker or user of the device.

To the bar 22 and the arch 20, I secure a suspension bolt 24 which extends upwardly through the top 25 of the refrigerator and 95 enters a meter or register case 26. A collar 27 is fitted upon the upper end of this suspension bolt and a spring 28 is coiled around the bolt between the top of the refrigerator and the said collar so as to tend to hold the 1

ice carrier toward the top of the ice chamber. A nut 29 is fitted on the upper extremity of the suspension bolt and bears upon the said collar so as to adjust the tension of the spring and thereby secure accuracy in the registering and indicating mechanism. The collar 27 is provided with a rack 30 on one side which meshes with a segment 31 on one end of a lever 32 which is fulcrumed within the meter casing and is provided at its free end with a pointer or indicator finger 33 playing in a slot 34 formed in the front face of the meter casing and having graduations thereon which are intended to indicate the weight of the ice in the ice-box. These graduations are numbered consecutively from zero at the lower end to 100 at the upper end and it will be readily understood that the weight of the ice upon the ice carrier at any time will be indicated by the numeral or graduation adjacent which the indicator 33 appears. Upon the side of the collar 27 opposite the rack 30 is a similar rack 35 which meshes with a gear wheel 36 forming one member of a train of registering mechanism which may be of any well known form, the said gear wheel 36 being connected with its shaft by suitable ratchet means so that when the ice cage descends, under the weight of the ice placed therein, the registering mechanism will not be actuated but as the ice is consumed and the ice-carrier thereupon rises, the registering mechanism will be actuated so as to accurately indicate the total quantity of ice consumed. The several shafts of the registering mechanism will be provided with pointers, indicated at 37, and the meter casing will be entirely closed except for a glazed front through which the meter may be read by the ice dealer at intervals.

My improved device is exceedingly simple in the construction and arrangement of its parts and will occupy very little space within the refrigerator so that the capacity of the same will not be diminished. When the door of the ice chamber is closed, the projections 3 and 4 thereon will bear against the cams or projections 5 and 6 at the front ends of the controlling bars 7 and 8 and will, consequently, move said bars laterally away from the rails on the sides of the ice carrier and the weight of the ice upon the carrier will then be supported by the suspension bolt and the spring coiled around the same. When the carrier is loaded to its capacity the spring 28 will be compressed and the suspension bolt will be at the lower limit of its movement with the lever 32, consequently, in its uppermost position so that the indicator 33 will show that the ice chamber is filled. As the ice is consumed, the spring will expand so as to raise the ice

carrier and will move the indicator to a lower point upon the adjacent scale as will be readily understood. When the door 2 is opened the brackets 3 and 4 will be moved away from the projections 5 and 6 and the springs 13 and 16, consequently permitted to expand and swing the controlling bars 70 toward the adjacent rails. The bar 8 will serve as a brake to prevent dropping of the carrier until the projection 15 upon the bar 7 engages the rack teeth 14 upon the adjacent rail 12 and thereby positively locks the 75 carrier against movement.

Having thus described the invention, what is claimed as new, is:—

1. The combination of a refrigerator, an ice carrier therein, controlling bars mounted within the refrigerator at the sides of the ice carrier, means for causing said bars to engage and hold the ice carrier, a door for the refrigerator, and means on said door for releasing said controlling bars from the ice 85 carrier.

2. The combination of a refrigerator, an ice carrier mounted therein, a track secured within the refrigerator, a rail on the ice carrier moving in said track, a controlling bar 90 mounted within the refrigerator and passing through the track, means for causing said bar to engage said rail, a door for the refrigerator, and means on the door for holding the bar out of engagement with the 95 rail.

3. The combination of a refrigerator, a track therein, an ice carrier having a rail movable along said track, a controlling bar mounted within the refrigerator, a spring 100 bearing upon said bar to cause the same to engage said track, a door for the refrigerator, and a projection on said door adapted to bear against the free end of said controlling bar and hold it out of engagement with said 105 rail.

4. The combination of a refrigerator, a vertically movable ice carrier mounted therein, and comprising a pan, standards rising from the pan, and a cross bar connecting the standards, means for permitting and controlling vertical movement of the said ice carrier, and a yieldable suspension device connected to the cross bar at the top of the carrier and mounted in the top of the re- 115 frigerator.

5. The combination of a refrigerator, a weight indicator mounted on the refrigerator, an ice carrier mounted within the refrigerator, a suspension bolt secured to the 120 top of said carrier and extending through the top of the refrigerator, a spring coiled around said suspension bolt above the refrigerator, and a tension device mounted upon the bolt and bearing upon said spring 125 and adapted to actuate the weight indicator.

6. The combination of a refrigerator having an ice chamber, an ice carrier in said chamber, a door for said chamber, and means whereby the ice carrier will be held
5 against movement when the door is opened and will be permitted to move when the door is closed.

In testimony whereof I affix my signature in presence of two witnesses.

GEORGE H. LANGEHENNIG. [L. s.]
